ATTORNEY

UNITED STATES PATENT OFFICE.

WILLIAM E. GALE, OF DALLAS, TEXAS.

AIRPLANE TAKE-OFF.

Application filed January 13, 1928. Serial No. 246,634.

This invention relates to aeronautics and more particularly to an automatic take off device or catapult for airplanes, the principal object being to provide an apparatus of the character specified to enable an aviator to take off where no straightaway of sufficient length is convenient, as, for example, on board ship.

Another object of the invention resides in the provision of a central tower and a revolving superstructure capable of constraining one or more ships to move in a circular path until such time as the said ships have attained sufficient momentum to enable them to be released in mid-air, whereupon they may assume a straight course solely under their own propelling power.

Still another object of the invention resides in the provision of a release, which may either be actuated by the occupant of the plane, when the plane has cleared the ground sufficient to enable it to be released, or by a ground attendant upon signal from the flyer.

Still another object of the invention resides in the provision of a novel releasing means, adapted, when in operation, to hold the plane in an equi-balanced position in accordance with the required banking of the plane as the latter follows the circular course to which it is held by the invention in gaining cruising speed.

With the foregoing objects as paramount, the invention has special reference to its salient features of construction and operation of parts to become manifest as the description proceeds, taken in connection with the accompanying drawings wherein:—

Figure 1 represents an elevational view of an airplane take off apparatus embodying the principles of the invention.

Figure 2 is a fragmentary detail view of the rotating housing at the top of the tower.

Figure 3 is a side elevational view of a plane equipped to co-operate with the invention.

Figure 4 is a detail view of a form of releasing means embodying the invention, and

Figure 5 is a detail view of a form of lever and push rod for actuating said releasing means.

In proceeding further, it may be stated that a considerable number of modifications as to details in the construction of the invention may be resorted to from time to time to improve upon the efficiency of the same, it being intended herein to simply set forth

the broad example of starting a plane in a restricted area, constraining the same to move in a circular path, and holding the plane until the latter attains cruising speed. 60

In the drawings 1 designates a central tower which must of necessity be of considerable height in order that the plane, designated by the character 2, in gaining speed, may swing outward sufficient distance to rise 65 to a safe level above the ground. The tower is constructed of riveted structural steel so as to possess the necessary strength in sustaining the weight of one or more planes of average weight and their fuel load. 70

Rotatably mounted upon the tower 1 is a superstructure 3 in the form of lateral beams constructed also of structural steel. In order to absorb excess friction, a cone shaped housing 4 is provided near the top 75 of the tower to which the structure 3 is affixed in the manner shown in Figure 1. This housing, as apparent in Figure 2, has an annular recess 5 in which reposes the anti-friction balls 6, intermediate the shoulder 80 formed on the top of the tower and a plate 7 affixed to the housing 4. Integral with the housing is a cylindrical element 8 provided with eyes 9 to which are connected cables 10, the latter extending between 85 pulleys 11 and 12, the latter being a restraining pulley, near the outer ends of the beams 3. To the ends of cables 10 is connected the planes 2, the manner of connecting to become apparent later. 90

Due to the enormous weight of the superstructure 3, provisions are made by which it may first be started to revolving slowly, since it would be a difficult matter to initially start the same by the plane itself. An 95 electric motor 13 is provided, revolving, through gears (not shown) in gear box 14, the vertical shaft 15, shown in Figure 2. Rotating power is thus transmitted to lateral shaft 16 through beveled gears 17, in turn 100 rotating pinions 18 on the ends of the shaft 16, the latter enmeshing crown gear 19 on the underside of the housing 4. Hence, the housing is rotated.

With reference now to the means for holding and releasing the planes, reference is made to Figures 3, to 5 inclusive. In order to be successfully operated by the invention, a plane is required to have securely connected thereto, with proper re-inforcement, 110 rings 20, to which short, but very strong and durable pieces of cable 21 are connected.

These pieces of cable, preferably of steel wire, also have rings 22 in their free ends, and are adapted to remain intact as illustrated in Figure 3.

- 5 As illustrated in Figure 4, a cross bar 23 is connected by linked rings 24 to each of the depending ends of the cables 10, and the bar 23 is arranged to be freely turned in the sleeve 25 to which one of the rings 24 is 60 affixed. Carried upon the extreme outer ends of the bars 23 are hooks 26, engaging operatively into the rings 22 carried by the short sections of cable 21 forming permanent connections on the plane.
- 10 15 Arms 27 rigidly affixed to the cross bar 23 opposing the sleeve 25 have connected to their outer ends a smaller cable 28, held by loops 29 relative to the larger plane suspending cables 10. These releasing cables 20 28 also extend over pulleys in the ends of the beams 3, but completely across the structure in the manner shown in Figures 1 and 2. The object is to exert a pull upon the cable 28 of equal force on its either end, and simultaneously, in order that the bars 23 will be 25 rotated simultaneously by the arms 27, to cause the hooks 26 to withdraw from the rings 22 carried by the cables 21 at the same time, which action will obviously release 30 both points of securing of the plane simultaneously when the latter attains the required speed and is a safe level above the ground. To accomplish the above action, a 35 push rod 30 is provided centrally of the tower, provided with a bifurcated head 31, as seen in Figure 2 especially, which, when urged upwardly, engages and pushes upward on the cable 28, consequently causing the ends to recede, imparting a pull upon the 40 arms 27.

A simple form of compound lever 32, 45 separately illustrated in Figure 5 is considered to be sufficient to exemplify the principle involved. The push rod 30 is shown in this figure as being pivoted at *a* to the lever 32, while the lever is centrally pivoted at *b* to a base 33, in order that a downward thrust upon the free end of the lever will urge the 50 push rod upward to bring the head 31 into contact with the cable 28 to effect release of the plane suspended upon the cable 10 as aforesaid.

It is understood that the apparatus embodying the invention may be used on vessels and on landing fields with equally successful results, and moreover, if it is desired 55

or necessary that the planes be given a greater radius in which to gain cruising speed, the cables 10 may be just as effectively wound upon suitable drums in order 60 that they may be extended to swing the planes outward from the tower 1, gradually paying out the cables as the planes gather speed. It is further possible to effect means by which the aviator himself may release the 65 plane from the cable 10 when the planes attain a speed where such release may be accomplished without danger to the ship. These modifications however need not depart from the principles of the invention as 70 set forth in the foregoing description.

In operation, the cross bars 23 are connected by hooks 26 to rings 22 carried by the ends of cables 21. The motors of the planes 2 are started; at the same time starting the 75 motor 13 in the tower. The planes are started moving as the motor 13 begins rotating the central shaft 15 to begin moving the beams 3. The beams are carried around at the same speed as that of the planes until 80 the latter have gained sufficient speed as to carry the beams alone. The motor 13 may then be stopped, as the planes gather speed, each moving at the same rate of speed.

It is required of the pilot to set his controls to accord with the circular line of travel to which the plane is held by the cables 10, and each plane is operated accordingly. Having attained sufficient speed for 85 safe release, a signal from the pilot will instruct the attendant on the ground to actuate the lever 32 to effect release of the planes simultaneously, provided two are being sent up, allowing them to resume a 90 straight course.

95 What is claimed is:

An air-plane take-off apparatus including a tower; a revolving member mounted atop said tower and having means for joining cables thereto; means carried by the opposite ends of said cables to effect their connection with the body of an air-plane, whereby the latter will be constrained in ascending to encircle said tower to gain cruising speed; means to allow said plane to assume 100 natural flying angles when so constrained, and ground means for effecting release of said plane from the cables when such speed has been attained.

105 In testimony whereof I affix my signature.

WILLIAM E. GALE.
